FRED M. SLATER, OF EASTON, PENNSYLVANIA, ASSIGNEE TO INGERSOLL-RAND COMPANY, OF JERSEY CITY, NEW JERSEY, A CORPORATION OF NEW JERSEY.

EXHAUST-CONTROLLING VALVE FOR PERCUSSIVE TOOLS.

1,278,237.

Specification of Letters Patent. Patented Sept. 10, 1918.

Application filed December 31, 1914. Serial No. 878,830.

To all whom it may concern:

Be it known that I, FRED M. SLATER, a citizen of the United States, residing at Easton, in the county of Northampton and State of Pennsylvania, have invented a certain new and useful Improvement in Exhaust-Controlling Valves for Percussive Tools, of which the following is a specification.

This invention relates to fluid operated percussive tools, and more particularly to valve mechanism for controlling the exhaust in such tools.

The object of this invention is to provide a valve mechanism for controlling the exhaust from alternately supplied portions of the cylinder independently of the mechanism for admitting fluid to the cylinder.

This object is accomplished by the invention, practical embodiments of which are shown in the accompanying drawings, in which:

Figure 1 shows a longitudinal section through the complete tool.

Fig. 2 and 3 show diagrammatic views of the piston and valve in different positions,

Fig. 4 is a detail perspective view partly broken away to show the construction of the valve mechanism,

Fig. 5 is a longitudinal section of a modified form of the invention, and

Fig. 6 is a diagrammatic view of the piston and valves of the form shown in Fig. 5 in a different position from that shown in Fig. 5.

In the drawings the tool is shown as a rock drill, comprising a cylinder 1, having a cylinder chamber made up of two connected bores, a rearward bore 2, of comparatively small diameter, and a forward bore 3, which is of considerably larger diameter.

In the cylinder 1 reciprocates a piston which is made up of a larger forward head 4 sliding in the bore 3, and a smaller rearward head 5 sliding in the bore 2, there being a neck 6 of smaller diameter than the head 5 between the heads 4 and 5 of the piston.

Fluid is admitted constantly to the rearward end of the smaller bore 2 by a passage 7, so that there is a constant pressure on the rear face of piston head 5 during the operation of the drill.

From the rear end of bore 2 fluid is admitted alternately to opposite portions or ends of the larger bore 3 to exert pressure alter-

nately on opposite sides of the larger head 4, admission to the forward end of the bore 3 taking place through the port 8 and the passage 9 when the rear face of the head 5 has uncovered the port 8 on the forward stroke of the piston, and admission to the rear end of bore 3 taking place through the passage 10 and port 11 when the forward face of head 5 uncovers the port 11 on the rearward stroke of the piston, the fluid flowing past the neck 6 into the rear end of the bore 3.

To exhaust the fluid from the opposite ends of the bore 3, the following mechanism is provided. On the side of the cylinder 1 is a valve chest 12, which is provided with a smaller central chamber 13 constantly connected by the port 14 with atmosphere. On either side of the chamber 13 are enlarged end chambers 15 and 16, which are connected by passages 17 and 18, respectively, with the rearward and forward ends of the cylinder bore 3. From the chambers 15 and 16 ports 19 and 20 open into the chamber 13, the inner faces of these ports forming valve seats 21 and 22. Sliding on a spindle 23 mounted centrally of the valve chest is a check valve 24 having a hollow central hub, which is provided with flanges or heads 25 and 26 preferably in the form of flat disks which are maintained somewhat farther apart than the valve seats 21 and 22, and are so arranged to seat on valve seats 21 and 22, that when one of the ports 19 and 20 is open the other will be closed. The cylinder bore 3 is also provided with an auxiliary exhaust port 27, which opens directly into the chamber 13 and hence is always in free communication with the atmosphere through the port 14.

In the operation of the drill, the parts being in the positions shown in Fig. 2, fluid is being admitted to the forward end of the cylinder bore 3 from the constant pressure portion of the cylinder through the port 8, and passage 9. Since there is pressure on the head 26 of the valve 24 tending to move it to close the port 20 and no pressure on the opposite head 25 of the valve 24, the port 27 being open to atmosphere and hence the rear end of bore 3 being under no pressure, the valve 24 will have taken the position shown in this Fig. 2, the head 26 closing the port 20 in the manner of a check valve and the

- port 19 being open, allowing free passage of the fluid from the back end of the cylinder bore 3 to atmosphere. The pressure exerted on the forward face of the piston head 4 will therefore move the piston rearwardly against the constant pressure on the smaller head 5, the fluid from the rear end of the bore 3 exhausting through passage 17, port 19, chamber 13 and port 14 to the atmosphere. When the piston reaches a point near the end of its rearward stroke, the forward face of the head 5 will uncover the port 11, the rearward face of the head 5 having previously covered the port 8 and cut off the admission to the forward end of the cylinder bore 3. The opening of port 11 will permit fluid to flow past the neck 6 into the rear end of the bore 3. Practically coincident with the opening of the port 11, the forward face of the piston head 4 will uncover the port 27 permitting the exhaust of fluid from the forward end of the bore 3 to atmosphere through port 14. As the port 19 is still open, fluid from the rear end of the bore 3 will start to flow through the passage 17 and out through port 19 to atmosphere. This flow will however carry the valve 24 and its head 25 with the flow in the manner of a check valve, the movement of the valve at the same time causing the head 26 to move off valve seat 22 and open the port 20. It will be seen that at this time, since the port 27 is open, to the forward end of the cylinder bore 3, there is no pressure on the face of head 26 so that the movement of the valve to the position shown in Fig. 3 will take place without resistance, this movement being accomplished with the loss of a very small amount of live fluid through the port 19 before the valve is moved. There being now pressure on the rear face of piston head 4, as well as on the small head 5, the piston will move forwardly, the fluid in front of the piston head 4 exhausting freely through the port 20 until the piston reaches the position shown in Fig. 2, whereupon the valve 24 will move to the position shown in Fig. 2, and the cycle of operations above described will then be repeated.
- In Figs. 5 and 6 a modified form of the invention is shown in which the pressure is constantly admitted through the passage 7 to the rearward portion of large cylinder bore 3, fluid being alternately admitted to the rear end of bore 2 by a port 28 and passage 29 from the rearward end of bore 3 past the neck 6 near the end of the rearward stroke of the piston, and fluid being admitted intermittently to the forward end of bore 3 by a port 30 and passage 31, when the piston nears the end of its forward stroke. In this form, the passage 17 leads to the chamber 15 from the rearward end of the small bore 2, while to take the place of port 27 the passage 32 leads from a port 33 un-

covered by the piston near the end of its rearward stroke while a passage 34 leads from a port 35 near the central portion of the small bore 2, which is uncovered by the piston near the end of its forward stroke, the passages 32 and 34 communicating with the atmosphere through the port 14.

The operation of this form is substantially the same as described with regard to the modification shown in Figs. 1 to 4, inclusive, the difference being merely in the position of the alternately supplied portions of the cylinder.

Although the invention is shown in connection with a drill in which the admission to both alternately supplied portions of the cylinder is controlled in a particular manner directly by the movement of the piston in the manner of a so-called "valveless" tool, it is suitable for tools in which the admission is controlled in other manners by the piston, or for tools in which the admission to one or both ends is controlled by a valve mechanism. It is, however, particularly adapted to drills of the type in connection with which it is herein shown, as it allows a free exhaust from the forward end of the cylinder during the forward stroke of the piston, permitting a heavy, uncushioned blow by the piston, and, at the same time, allows a free exhaust from the rearward end of the cylinder, eliminating a considerable cushioning effect, and reducing the amount of power necessary to effect the rearward stroke of the piston.

It is to be understood that while this present showing and description discloses certain specified modifications of the invention, other forms and modifications are included in the spirit and scope of the same, as expressed in the claims.

What I claim is:

1. In a fluid operated percussive tool, a cylinder, a piston, admission ports directly opened and closed by said piston for alternately admitting motive fluid to the opposite ends of the cylinder, a valve casing, passages constantly connecting the ends of the valve casing with the respective ends of the cylinder, an exhaust port constantly connecting the central portion of the valve casing with the atmosphere, a spindle extending longitudinally of the valve casing, and a check valve sliding on said spindle in each end of the valve casing to open and close communication alternately between the ends and the central portion of the valve casing.
2. In a fluid operated percussive tool, a cylinder having a bore of two diameters, a piston in said cylinder having two surfaces for driving it forward and one for driving it rearward, a passage for constantly supplying motive fluid against one of said two forwardly acting surfaces, a piston controlled passage for intermittently supplying

- motive fluid against the other of said two forwardly acting surfaces, a piston controlled passage for intermittently supplying motive fluid against the surface for driving the piston rearward, a valve casing, passages constantly connecting the ends of the valve casing with the respective ends of the cylinder, an exhaust port constantly connecting the central chamber of the valve casing with the atmosphere, a spindle extending longitudinally through the valve casing, and a check valve sliding on said spindle in each end of the valve casing to open and close communication alternately between the end chambers and the central chamber of the valve casing.
5. In a fluid operated percussive tool, a cylinder, a piston, admission ports directly opened and closed by said piston for alternately admitting motive fluid to the opposite ends of the cylinder, a valve casing having a central chamber and end chambers, valve seats formed on the ends of said central chamber, passages constantly connecting said end chambers of the valve casing with the respective ends of the cylinder, an exhaust port constantly connecting the said central chamber of the valve casing with the atmosphere, a check valve in each end chamber of the valve casing, said check valve consisting of flat disks having a hollow central hub, a spindle centrally located in respect to each end chamber and passing through said central hub of the check valve, so that the check valve can slide on said spindle and thus advance against the valve seats or recede therefrom, to open or close communication between said end chambers and the said central chamber of the valve casing, the flat disks being maintained farther apart than the distance between the valve seats, so that when one disk is seated the other is held away from its seat.
10. In a fluid operated percussive tool, a cylinder, having a bore of two diameters, a piston in said cylinder having two surfaces for driving it forward and one for driving it rearward, a passage for constantly supplying motive fluid against one of said two forwardly acting surfaces, a piston controlled passage for intermittently supplying motive fluid against the other of said two forwardly acting surfaces, a piston controlled passage for intermittently supplying motive fluid against the surface for driving the piston rearward, a valve casing having a smaller central chamber and enlarged end chambers, passages constantly connecting the enlarged end chambers of the valve casing with the respective ends of the cylinder, an exhaust port constantly connecting the smaller central chamber of the valve casing with the atmosphere, a spindle extending longitudinally through the valve casing, and a check valve sliding on said spindle in each
15. enlarged end chamber of the valve casing to open and close communication alternately between the enlarged end chambers and the central chamber of the valve casing.
20. 4. In a fluid operated percussive tool, a cylinder, a piston, admission ports directly opened and closed by said piston for alternately admitting motive fluid to the opposite ends of the cylinder, a valve casing having a central chamber and end chambers, valve seats formed on the ends of said central chamber, passages constantly connecting said end chambers of the valve casing with the respective ends of the cylinder, an exhaust port constantly connecting the said central chamber of the valve casing with the atmosphere, a check valve in each end chamber of the valve casing, said check valve consisting of flat disks having a hollow central hub, a spindle centrally located in respect to each end chamber and passing through said central hub of the check valve, so that the check valve can slide on said spindle and thus advance against the valve seats or recede therefrom, to open or close communication between said end chambers and the said central chamber of the valve casing, the flat disks being maintained farther apart than the distance between the valve seats, so that when one disk is seated the other is held away from its seat.
25. 5. In testimony whereof, I have hereunto set my hand.
30. 6. FRED M. SLATER.
35. Witnesses:
